Primary Examiner — Lauren R Calve*(74) Attorney, Agent, or Firm* — John M. Lipchitz(57) CLAIM

The ornamental design for a shaving razor cartridge container, as shown and described.

DESCRIPTION

FIG. 1 is a top perspective view of a shaving razor cartridge container showing our new design;
 FIG. 2 is a front view thereof;
 FIG. 3 is a rear view thereof;
 FIG. 4 is a right side view thereof;
 FIG. 5 is a left side view thereof;
 FIG. 6 is a top view thereof;
 FIG. 7 is a bottom view thereof; and,
 FIG. 8 is a bottom perspective view thereof.

The dashed lines shown illustrate portions of the shaving razor cartridge container and form no part of the claimed design. The dot-dash-dot lines shown represent a boundary between the claimed and unclaimed subject matter and form no part of the claimed design.
